UNITED STATES PATENT OFFICE.

OTTO HIRR, ELEODORO AVILÉS, AND ARCADIO FORERO, OF BUENOS AIRES, ARGENTINA.

SIGN FOR ADVERTISING AND THE LIKE.

Application filed July 18, 1927, Serial No. 206,713, and in Argentina May 31, 1927.

The present invention relates to certain improvements in signs of the type constituted by continuous tubes through which circulates a stream of liquid which may or 5 may not be interrupted at points by bodies of air; the chief object of the invention being to simplify the operation of the apparatus and to reduce its cost of manufacture and maintenance.

10 Another object of the invention is to construct the signs in such a way as to render them luminous, whereby noteworthy effects are obtained during the night.

Other objects of the invention will appear 15 as the present specification proceeds and will be specifically claimed.

In order that the present invention may be clearly understood and readily carried 20 into practice the preferred form thereof has been illustrated in the accompanying drawing in which:

Fig. 1 shows diagrammatically the general arrangement of the apparatus, as well as all 25 its elements, in accordance with the present invention.

Fig. 2 is a diagrammatic sectional view on line *a*—*b* Fig. 1 of the casing enclosing the sign and its actuating means, and finally

Fig. 3 illustrates a centrifugal pump 30 which may be used advantageously for circulating the stream of liquid and air continuously through the apparatus.

In all these figures, like reference numerals indicate like or equivalent parts.

According to the invention, the sign is 35 actuated by means of an electric motor 1 or its equivalent, the shaft 2 of which drives two centrifugal pumps 3 and 16, arranged in line, but it is to be understood that such 40 number is not limitative but may be increased or reduced, according to the number of different colours which must appear on the sign, as hereinafter explained.

The pump 3 draws in the liquid contained 45 within a tank 5 through a pipe 4 the lower end of which is arranged near the bottom of the said tank, the pipe 4 being in communication with a branch 6 through which air is drawn in simultaneously from the atmosphere. The mixture of air and liquid leaves 50 the pump through a pipe 7 and enters the lower end of a small cylindrical balancing vessel 8, the liquid collecting at the lower part thereof, while the air passes to its upper 55 part indicated at 9. Through the compres-

sion created within the said balancing vessel by the air, the liquid is forced through a pipe 10, the lower end of which terminates in proximity to the bottom of the vessel. This pipe 10, which is provided with a 60 small port 11 through which the air enters the pipe from the air space 9, leads to the letters 12 forming the sign and, after travelling through the entire path thereof, the mixture of air and liquid returns through a 65 pipe 14 to the upper part of the tank 5. The letters are arranged on a base plate 13 hereafter described.

The lower part of the small balancing vessel 8 is connected by a return pipe 15 to 70 the tank 5, which pipe is provided with a suitable constriction in order to regulate the pressure within the said vessel by forcing part of the liquid in the vessel to flow back to the tank through the said pipe. In this 75 way, it is possible to supply liquid and air as required, according to the cross-section or length of the glass tubing 12 of the sign, thus obtaining a regular circulation for any size of tubes used.

The liquid contained within the tank 5 80 may be of any suitable nature, and a colouring agent is added thereto so that it may be seen from the exterior when it flows through the pipes of the sign, the air bubbles contained in it giving a perfect appearance of mobility to the said letters or designs.

In the form illustrated, and with the object of giving the sign a greater variety, a 90 second pump 16 is shown, coupled to shaft 2, which draws in from the lower part of tank 18, through a pipe 17, the liquid therein contained and which is of, or has, a different colour than that of tank 5. The pipe 95 17 is connected with a branch 19 for drawing in air from the atmosphere. The liquid drawn in by the pump is impelled through pipe 20 to and within a small balancing vessel 21, preferably of cylindrical form, the liquid collecting at its lower part and the air rising to the upper part 22 on account of the difference in density. A pipe 23 opening into the said vessel, near its lower end or bottom and provided with a small port 100 24 serving the same purpose as the port 11 of pipe 10 as already described, carries the air and liquid to another part of the sign, formed by a pipe 25 which, in the present case, forms the frame or border thereof,

- said pipe being continuanted by pipe 26 for return to the upper part of tank or container 18. In order to maintain the necessary pressure within the balancing vessel 21, the 5 lower part thereof is connected, by means of a return pipe 38, to the upper part of tank 18, the adjustment of pressure being effected by way of a partial constriction, the same as described with reference to the pipe 15.
10. Both tanks 5 and 18 are provided with vents 27 which permit an excess of air to escape to the atmosphere, said vents serving also for re-filling the said tanks when necessary.
15. The centrifugal pumps employed may be of any suitable type, although quite satisfactory results have been obtained with that diagrammatically represented in Fig. 3. In accordance with this form, on the shaft 2 20 is mounted concentrically a circular disc 28 working within a circular cavity 29 eccentrically arranged with relation to the said disc and formed within the body of the pump and from which lead channels registering 25 with the pipes 4 and 7 as previously mentioned. The circular disc is formed with a number of radially disposed grooves 30 within which are housed the blades 31 the outer edges of which are constantly in contact with 30 the inner surface of the cavity 29 on account of the centrifugal action created by the shaft 2 during its rotation, whereby a vacuum and a pressure are created alternately, in the direction as indicated by the arrows of 35 Fig. 3.
- The shaft 2 rotates in bearings 32 formed in the interior of casings closing the bodies of the pumps 3 and 16, forming a substantially integral unit.
40. According to the present invention, the base plate 13 supporting the continuous glass tubes or pipes forming the letters or designs of the sign, is cut away totally or partially, as indicated at 33, in correspondence with the configuration with the said signs, to the object of permitting the passage through said cut-away parts and glass tubes, of light rays from a source of light, for instance, electric lamps 34 situated and arranged on a reflecting plate 35 which, in turn, is arranged within a casing 36 which, if desired, may house the current controlling parts 37 of the apparatus.
45. In this way, the effect of moving illuminated letters—by projection of light rays through the tubes or pipes forming such letters—is obtained.
- The operation will be clearly apparent to those skilled in the art, and needs no further explanation.
50. Evidently, various modifications of construction and other details may be made without departing from the sphere of the present invention which has been clearly defined in the appended claims.

We claim as our invention:—

1. An advertising or like device, comprising a base plate provided with transparent piping representing indicia; a tank to contain liquid; a transmission piping system leading from said tank to the indicia piping and from the latter back to the tank, such system embodying a balancing vessel, a delivery section leading thereto from the tank, a supply section leading to the delivery section for admitting gaseous fluid to the latter section to be introduced, together with liquid from said tank, into the balancing vessel and to separate in said vessel from the liquid, a discharge section leading from the balancing vessel to the inlet end of the indicia piping and having an inlet port for the separated fluid within the confines of the vessel, and a return section leading from the outlet end of said indicia piping back to the tank; and a pump connected to said delivery section for continuously circulating a stream of liquid and gaseous fluid completely through the transmission piping system and the indicia piping. 70
2. An advertising or like device, comprising transparent piping representing indicia; a tank to contain liquid; a transmission piping system leading in a closed path from the tank to the indicia piping and from the latter back to the tank, such system including means for introducing a gaseous fluid thereinto to produce spacing bubbles in the liquid; and a rotary centrifugal pump connected to the transmission piping for continuously circulating a stream of liquid and gaseous fluid completely through the indicia and transmission piping. 80
3. An advertising or like device, comprising transparent piping representing indicia; a tank to contain liquid; a transmission piping system leading in a closed path from the tank to the indicia piping and from the latter back to the tank, such system including means for introducing a gaseous fluid thereinto to produce spacing bubbles in the liquid, and also including a balancing vessel wherein the liquid and the gaseous fluid separate in the lower and upper portions of the vessel to regulate the pressure therein; and means connected to said transmission piping for circulating the liquid and gaseous fluid completely through the indicia and transmission piping. 90
4. An advertising device, according to claim 3, in which the transmission piping includes a section having its inlet portion disposed in the balancing vessel and terminating adjacent the bottom thereof and provided with an inlet port for the separated fluid within the confines of the vessel; the outlet portion of such section leading to the inlet end of the indicia piping. 100
5. An advertising or like device, comprising transparent piping representing

indicia; a tank to contain liquid; a transmission piping system leading in a closed path from the tank to the indicia piping and from the latter back to the tank, such system including means for introducing a gaseous fluid thereinto to produce spacing bubbles in the liquid, and also including a balancing vessel wherein the liquid and the gaseous fluid separate in the lower and upper portions of the vessel to regulate the pressure therein; and a rotary centrifugal pump connected to the transmission piping for continuously circulating a stream of liquid and gaseous fluid completely through the indicia and transmission piping.

6. An advertising device, according to claim 5, in which the transmission piping includes a section having its inlet portion disposed in the balancing vessel and terminating adjacent the bottom thereof and provided with an inlet port for the separated fluid within the confines of the vessel; the outlet portion of such section leading to the inlet end of the indicia piping. 20

In testimony whereof we affix our signatures. 25
